Des. 203,258
Patented Dec. 21, 1965

203,258

FOUR SLEEPER CAMPER

Frank E. Mann, 5430 W. 43rd St., Houston, Tex.

Filed Mar. 31, 1965, Ser. No. 84,545

Term of patent 14 years

(Cl. D14—3)

FIG. 1 is an isometric view of the top, front and one side of a four sleeper camper showing my new design; and

FIG. 2 is an isometric view of the top, rear and the other side thereof.

I claim:

The ornamental design for a four sleeper camper, as shown.
